GEORGE E. GELM, OF JAMESTOWN, NEW YORK.

TORPEDO FOR BLASTING PURPOSES.

1,406,844.

Specification of Letters Patent. Patented Feb. 14, 1922.

Application filed March 25, 1921. Serial No. 455,677.

To all whom it may concern:

Be it known that I, GEORGE E. GELM, a citizen of the United States, of Jamestown, county of Chautauqua, State of New York, have invented certain new and useful Improvements in Torpedoes for Blasting Purposes; and I do hereby declare the following to be a full, clear, and exact description of the invention, such as will enable others skilled in the art to which it appertains to make and use the same.

My present invention relates to improvements in torpedoes more especially for use in blasting or shooting oil or gas bearing sands or other strata encountered in drilling or boring wells for petroleum or gas, or for artesian wells, or mining, or other purposes, in which an explosive charge is required of comparatively great length and narrow cross section. In boring wells of the character described the diameter of the bore is necessarily very limited, being ordinarily a few inches only, generally about five or six inches more or less, and in order to secure the desired effect of the explosion a considerable weight of high explosive must be used.

Since the diameter of the container for the charge must necessarily be somewhat less than the diameter of the bore of the well it becomes necessary, if the desired weight of high explosive is to be used, to make the charge very long, varying under conditions from say twenty to thirty feet or more; the explosive charge being in the form either of a solid column or a series of segments forming a built-up column. If such a long column of high explosive is exploded from the top, as in the ordinary practice, the upper portion only of the charge would be detonated, and the lower portion is blown away and is consumed rather by quick combustion than by detonation; the result being that with the apparatus now generally in use there is a limit to the efficiency of charges of this character dependent more or less upon the length of the charge relative to the diameter of the same, and the desired results are not satisfactorily secured by merely increasing the amount of the charge by lengthening the column of high explosive.

According to my invention I provide a torpedo of great length compared to its diameter, and containing a column of high explosive, which column is provided with a small central bore, which bore is filled with

a booster or primer charge of such material as may be instantaneously detonated throughout its length, and thereby transmitting the explosion to the surrounding charge of high explosive, detonating the same and causing the entire mass of high explosive contained in the torpedo, by the instantaneous detonation aforesaid, to exert the maximum explosive effect within desired limits in the confined area.

The booster charge may be exploded electrically or mechanically in any convenient way.

My invention will be more clearly understood after reference to the accompanying drawings, which are typical of the various constructions proposed, and in which like parts are indicated by similar reference symbols throughout the several views.

Figure 1 shows a section through a pair of superposed torpedoes, each containing an integral main charge with a central booster charge for detonating the same, the lower torpedo being shown in dotted lines, and the booster charge for the upper torpedo being arranged to be ignited by electricity, parts being broken away.

Figure 2 is a similar view to Figure 1, except that the explosive column in a single casing is made up of a series of cylindrical sections.

Figure 3 is a similar view to Figure 1, except that a mechanical arrangement for igniting the booster charge is provided, and the container is shown with a bail for use in lowering same and with a pointed tip at the base; and

Figure 4 is an enlarged sectional view of the top of Figure 3, both the main charge and the booster charge being omitted to more clearly show the construction of the parts.

Referring first to Figure 1, A represents the container which is preferably in the form of a cylindrical casing, made of thin material of sufficient strength and rigidity to hold a long column of high explosive B, which is placed therein in any convenient way as by being cast, molded or packed therein. In order to conveniently form a bore in this mass, a central rod may be projected through the centre while the main charge B is being put in place, and this rod is removed leaving a central perforation C, the walls of which may be coated in any

convenient way, if desired, or left as they stand.

The bottom of the casing A is closed by the bottom plate E, which may be provided 5 with a central opening e, and this opening may be closed by a smaller plate e', which plate may be on either the inside or outside of plate E.

The object of said hole e is that by removing 10 or puncturing plate e' the two exposed ends of the booster charge contained in superposed casings are brought into communication. This occurs when two or more torpedo casings are used end to end to form a 15 longer charge, than where a single casing is used. Such an arrangement is shown in dotted lines in Figure 1.

The upper portion of the bore C is preferably expanded, as at C', to form an enlarged head or chamber for the booster charge. This chamber may be surrounded with a receptacle F, circular in cross section, and provided with a flange f adapted to be attached to the upper head H of the 25 container, which head is perforated, as at h, to receive the leading-in wires I connected to the electric fuse or primer K.

The electricity is carried down to the torpedo through the well by any suitable cable, 30 not shown, in the usual way.

In the modification shown in Figure 2 instead of having the main charge in each torpedo in the form of a single homogeneous column, the column is divided up into a series 35 of sections B', each of which is centrally perforated, as at C, and these perforations are filled with a booster charge D. These sections may be placed directly one upon the other or may be separated from each other 40 by disk-shaped partitions such as b. These disks may be of such material as to be perforated in the centre by the force of the explosion when the booster charge D is exploded, or they may be punctured or weakened 45 at the center b^o when the sectional charges are inserted. It may be more convenient to assemble the charge in this way, but the essential result is the same in both cases, that is, we have a substantially homogeneous column of high explosive provided 50 with a centrally disposed detonating charge which extends through the axis of the cylindrical column.

In the form shown in Figures 3 and 4, the 55 main charge may be either homogeneous, as shown at B, or built up in sections as shown at B' in Figure 2. The central column of detonating material is shown as terminating near the bottom E of the casing A, but it 60 may be carried all the way through as shown in the former figures. In this form of the device I have shown a bail L for convenience in lowering the torpedo down in the well, and the conical tip M to facilitate guiding 65 the lower end of the torpedo as it passes

down in the well. This tip may be left empty as shown, or filled with suitable explosive.

Since it may be inconvenient, especially in shooting deep wells, to lead an electric cable 70 down to the torpedo for the purpose of operating the detonator, I may provide a mechanical arrangement for detonating the booster charge, such as is shown in detail in Fig. 4, in which F' represents a chamber 75 which includes the upper portion of the booster charge as shown in Fig. 3, and into this chamber the detonator K' projects which is carried by the screw holder K², carried by the lower end of the sleeve P which is 80 cured into the socket h in the head H.

The holder K² carries a detonator K', the head of which is adapted to be struck by the firing pin n carried by the lower end of the plunger N, which plunger is normally 85 held in the safety position in the sleeve P by means of the shear pin O. The detonator is held in the holder by means of a screw-threaded ring k^o. This plunger N carries a disk-shaped head N' which is 90 adapted to be struck by the point of some fixed object, such as the well known "go-devil" which, when dropped into the well, will strike said head and will drive the plunger N down, shearing the safety pin O 95 and exploding the detonator K'.

It will be noted that the sleeve P and the parts carried thereby may be kept separate from the torpedo and only put in place just before the torpedo is lowered into the well. 100 The bushing h may be covered by any suitable cap or covering, not shown, which may be removed when it is desired to screw the sleeve P in place.

It will be obvious that the operation of 105 the device will be the same whether the torpedo be exploded electrically or mechanically, or whether used singly or in groups.

The charge of main explosive may be 110 molded, or packed or shaped in each torpedo in any convenient way, and the same is true of this charge when made up in the form of sections as shown in Fig. 2. The booster charge detonating the main charge may also be molded, packed or placed 115 in position in any convenient way. The booster charge is to be detonated by a primer or detonator which is normally kept separate from the torpedo and only inserted just prior to the use of the same. 120

In order to secure the factor of safety which is so important in devices of this character, I prefer to use those high explosives which are not of the sensitive nature, such, for instance, as trinitrotoluene. 125

For the main explosive charge I use trinitrotoluene, variously known as "trotyl," "trinol," "tritolo," "trilite" and "TNT"; or a mixture of trinitrotoluene (50 to 70 parts) with trinitroxylylene (50 to 30 parts); or 130

those other nitro aromatic compounds, trinitronaphthalene, trinitroaniline, and hexanitrodiphenylamine, or other suitable high explosive compound.

5 For the booster charge I use trinitrotoluene (TNT—granular—of a density of about 1.0); hexanitrodiphenylamine; trinitrophenylmethylnitramine or tetryl; tetranitroaniline, or other suitable booster compound.

10 The booster charge may be exploded by a detonator containing fulminate of mercury, lead azide, or the like, and said detonator may be operated either electrically 15 or mechanically, or in any other suitable way.

The above described arrangement of the main and booster charges will permit the efficient employment of a type of explosives, 20 formed in long cylindrical charges, that can be handled and transported with safety, and which can be stored for long periods under extreme temperatures without deterioration.

25 It will be noted that with all forms of the device all portions of the main charge of high explosive are within a short distance of the central booster charge, and this booster charge should be of such a composition that its detonation throughout its 30 length will be instantaneous, causing the surrounding particles of the main charge to be also instantaneously detonated so that there is no question of part only of the long 35 column of high explosive being detonated and the rest burned, but there is a complete detonation simultaneously of all the parts of the main charge, with the vastly more effective result obtained in the confined 40 space in the well where the explosion occurs.

It will be obvious that various modifications might be made in the herein described construction, and in the combination and arrangement of parts which could be used 45 without departing from the spirit of my invention; and I do not mean to limit the invention to such details except as particularly pointed out in the claims.

50 Having thus described my invention what I claim and desire to secure by Letters Patent of the United States is:—

1. A torpedo for blasting purposes, comprising an elongated cylindrical casing

closed at both ends, a main charge of high 55 explosive contained in said casing, said main charge being provided with an axial perforation therein, and a chamber at the upper end of said perforation, a booster charge filling said perforation and said 60 chamber, a detonator for said booster charge projecting into said chamber, and means for actuating said detonator, substantially as described.

2. A torpedo for blasting purposes, comprising an elongated cylindrical casing closed at both ends, a main charge of high explosive contained in said casing, said main charge being provided with an axial 65 perforation therein, and a chamber at the upper end of said perforation, a booster charge filling said perforation and said 70 chamber, a detonator mounted in said chamber, and means operable from a distance for actuating said detonator, substantially 75 as described.

3. A torpedo for blasting purposes, comprising an elongated cylindrical casing closed at both ends, a main charge of high explosive contained in said casing, and composed 80 of a series of cylindrical sections, each section of said main charge being provided with an axial perforation therein, and the upper section being provided with a chamber surrounding the upper end of said 85 perforation, a booster charge filling the perforation in each section and also filling said chamber, a detonator for said booster charge projecting into said chamber, and means for actuating said detonator, substantially 90 as described.

4. A torpedo for blasting purposes, comprising an elongated cylindrical casing closed at both ends, a main charge of high explosive contained in said casing, and composed 95 of a series of cylindrical sections, each section of said main charge being provided with an axial perforation therein, and the upper section being provided with a chamber surrounding the upper end of said 100 perforation, a booster charge filling the perforation in each section and also filling said chamber, a percussion detonator mounted in said chamber, and means operable from a distance for actuating said detonator, substantially 105 as described.

GEORGE E. GELM.
